Gilbert A. Crawford

UNITED STATES PATENT OFFICE.

GEORGE PIRNIE, OF NYACK, NEW YORK.

WHIP.

SPECIFICATION forming part of Letters Patent No. 375,950, dated January 3, 1888.

Application filed October 17, 1887. Serial No. 252,540. (No model.)

To all whom it may concern:

Be it known that I, GEORGE PIRNIE, a citizen of the United States, residing at Nyack, in the county of Rockland and State of New York, 5 have invented certain new and useful Improvements in Whips; and I do hereby declare that the following is a full, clear, and exact description of the invention, which will enable others skilled in the art to which it appertains to make and use the same.

In the manufacture of carriage-whips and other whips having a covered stock or handle the stock is usually composed of three concentric layers of material. The core or central portion is made of rattan, bone, or other suitable substance. Outside of the core or central portion is a middle lining of leather wound or wrapped around the central portion. An outer covering is then woven or plaited around the 20 middle lining.

The object of my invention is to produce a whip which shall be stronger, more durable, easier of manufacture, and neater in workmanship than any now in use. To this end I employ eel-skin as the material of the middle lining.

My invention is shown by the accompanying drawings, which are hereby made a part of this specification, and in which similar letters refer to similar parts.

Figure 1 is a vertical cross section of the stock of a "straight" whip. A is the core or central piece. B is the middle lining of eel-skin. C is the woven or plaited outer covering. D is a loop, to which the snapper is attached. This loop may be constructed in any suitable way.

Fig. 2 is a view of the finished whip, E being the snapper, which may be attached to the 40 loop D in any suitable manner.

In its preferred form I carry out my invention as follows: The eel-skin, when first removed from the eel, is stretched in such a way that it will stiffen and dry flat. Then without 45 any tanning or other treatment the dry skin is cut into long and narrow strips or ribbons about an inch wide. These strips of skin are soaked in water for several hours until they become quite soft and flexible. They are then 50 wound spirally upon the central piece of the stock in the usual way and by the usual means, and are held in place until dry by the common

expedient of winding twine about them. In drying the eel-skin shrinks strongly and clings snugly to the central piece, and when the eel-skin has thoroughly dried on, the twine may be removed and the skin will remain in place without the use of cement or other adhesive agent. Finally, the outer covering is plaited on and the whip is finished up in the usual 60 manner.

My invention does not consist merely in the substitution of eel-skin as the material for the middle lining, B. I am aware that the mere substitution of one material for another is not 65 a patentable invention; but in the application of eel-skin to whips I have discovered and brought into play qualities which, so far as I am aware, have not hitherto been known in eel-skin. I have simplified the process of 70 manufacture, and I have produced new and important results in the finished whip.

Heretofore it has been necessary to employ for the middle lining of whips only skins which have been tanned. The tanning has of course 75 added to the cost of the skin. Owing to the thinness of eel-skin and its flexibility when wet I am enabled to dispense entirely with the process of tanning. Again, in experimenting with the use of eel-skin for whips I have 80 discovered that the power of shrinkage resident in eel-skin is very great as compared with that of other skins. Now, skin linings have heretofore been fastened about the core or central piece by cement or some other adhesive 85 agent. By taking advantage of the shrinking power of eel-skin I dispense with this adhesive agent entirely, thus reducing both the cost and trouble of manufacture. Being wound while wet upon the core, the eel-skin in drying shrinks so much as to cling very tightly to the core, and when thoroughly dried the eel-skin will be held in its place about the core 90 simply by its own shrinkage. Again, all materials heretofore employed for the middle lining of whips have been too thick and have made the finished whip too bulky. Eel-skin being very thin, it rolls around the center more smoothly and thus makes the diameter of the stock less. The great shrinkage of the eel-skin 95 reduces the diameter of the whip still more, and at the same time produces a harder, firmer, and smoother surface on the stock. All these effects make the general workmanship of the 100

whip neater. In the case of straight whips intense shrinkage of the eel-skin has the further effect of straightening the top of the stock, so that the whip bends over less than any 5 whips heretofore made.

By the application of eel-skin to whips I have developed still another valuable quality in eel-skin not hitherto known, as I believe. This is its extreme oiliness. The amount of 10 oil contained in eel-skin is much greater than that contained in any other skin hitherto used for the lining of whips, and its oiliness is still further increased by using the skin untanned. The oily qualities of the eel-skin act in a very 15 striking manner both upon the core of the whip and upon its outer covering, at once rendering them flexible and less brittle, and preserving them from the effects of dampness. The oiliness of the eel skin and its very close 20 texture also preserve the bone core from the action of frost—a most important result. Nothing is more common than for whips to break in cold weather. An eel skin lining will largely prevent this. Finally, all these 25 results, coupled with the extreme toughness of eel-skin, render the whip vastly more durable than those formerly made. I may make the entire lining or inner wrapper, B, of eel-skin, or I may cover the core with eel skin for part 30 of the length of the core only, and may use a middle lining of some other material for the balance of the length.

My invention may be applied to what are known as "drop-top" whips, one of which is 35 shown in Fig. 3, in which the central portion, A, terminates some distance from the smaller end of the stalk, the remaining portion of the stalk being usually composed only of the lining B, prolonged and rolled like a cord, and

with the covering C tightly plaited around it, 40 thus being flexible enough to fall or "drop" over. I may make the drop part of the whip simply of the eel-skin lining and the covering, or I may use a cloth or other flexible central portion within the eel-skin lining. In these 45 whips, also, I may employ an eel-skin lining for only a part of the length of the whips. In either case most of the advantages will exist which are found in using eel-skin in straight whips. Indeed, my invention may be advantageously applied to any whip having a covered stock.

I do not limit myself to any of the methods of manufacture hereinbefore described; but I desire to cover all methods of employing eel-skin for the lining of whips.

Having described my invention, what I claim as new, and desire to secure by Letters Patent, is—

1. A whip one of whose wrappings or coverings is composed of eel-skin, substantially as and for the purposes set forth.
2. A whip consisting of the core or central portion, A, the middle lining, B, wholly or partly composed of eel skin, and the outer covering, C, substantially as shown and described.
3. A whip consisting of a hard core of rattan or other suitable material inclosed in a wrapping or middle lining wholly or partly composed of untanned eel-skin and with an 65 outer fibrous covering, the eel-skin being held in place merely by its own shrinkage, substantially as shown and described.

GEORGE PIRNIE.
